UNITED STATES PATENT OFFICE.

MILLARD F. WOODWARD, OF ALEXANDRIA, LOUISIANA.

INTERNAL-COMBUSTION ENGINE.

Application filed April 17, 1922. Serial No. 553,495.

To all whom it may concern:

Be it known that I, MILLARD F. WOODWARD, a citizen of the United States, residing at Alexandria, in Rapides Parish and State 5 of Louisiana, have invented new and useful Improvements in Internal-Combustion Engines, of which the following is a specification.

This invention relates to engines and more 10 particularly to bushings for the cylinders thereof.

The primary object of this invention resides in the provision of means adapted to abolish the customary practice of reborning 15 worn engine cylinders.

Another object of this invention resides in the provision of means adapted to abolish the necessity of disassembling the majority of working elements of an engine to re-establish 20 the original working condition of its cylinders.

A still further object of this invention resides in the provision of bushings, for the cylinders of engines, which can be readily 25 removed when worn and replaced by perfect bushings in the minimum length of time.

With these and other objects in view this invention resides in certain novel features 30 of construction and arrangement of elements to be hereinafter set forth in the specification, illustrated in the accompanying drawings and pointed out in the appending claim.

In the accompanying drawings.

Figure 1 is a vertical sectional view 35 through a conventional form of internal combustion engine with the elements of this invention therein.

Figure 2 is a plan view with the head of 40 the engine removed and the removable bushing in secured position.

Figure 3 is a similar view with the locking ring removed.

Figure 4 is a detail perspective view of the 45 upper portion of the cylinder of an engine with the head removed and the elements of this invention in juxtaposition therewith.

Figure 5 is a perspective view of the removable bushing positioned to illustrate the 50 locking key thereof.

Figure 6 is a detail sectional view on line 6—6 of Figure 3.

The drawings show but a single cylinder, though it will be understood that the engine 55 may be provided with as many cylinders as desired.

In these views 1 indicates the cylinder, the interior of which is made of larger diameter than the piston 2. At its lower end the cylinder is provided with a beveled seat 3 and at its upper end it is provided with an annular recess 4 and diametrically arranged notches 5 which communicate with the recess. A key slot 6 is also formed in the wall of the cylinder, the upper end of the slot opening out into the recess. A bushing 7 fits in the cylinder and is engaged by the piston. The lower end of this bushing is beveled, as at 8, to engage the beveled seat 3 and its upper end is provided with a key 9 for engaging the slot 6 so that the bushing cannot turn within the cylinder. The upper extremity of the bushing is reduced in diameter, as shown at 10, this reduced part forming a shoulder 11 which will lie flush 75 with the bottom of the recess 4 when the bushing is in place. A ring 12 fits in the recess and engages the shoulder 11 and surrounds the reduced part 10. This ring is provided with ears 13 which engage the notches 5 and the ring is held in place by the bolts 14 which extend through the ears and engage holes made in the cylinder. Thus the bushing will be securely held in place by the ring and it will be held against 80 rotary movement by the key. When the bushing is worn it is simply necessary to remove the ring and knock the bushing out of the cylinder. A new bushing can then be put in place and the ring replaced to hold 85 the new bushing in the cylinder.

By this invention it is unnecessary to re-bore a cylinder and the cylinder can be restored to its circular shape by simply removing the old bushing and substituting a 90 new one. Thus the cylinder can be restored to its true shape with the minimum amount of labor and expense.

It is thought from the foregoing description that the advantages and novel features 100 of my invention will be readily apparent.

I desire it to be understood that I may make changes in the construction and in the combination and arrangement of the several parts, provided that such changes fall within 105 the scope of the appended claim.

What I claim is:

In combination with a cylinder and its piston, a bushing fitting in the cylinder and engaged by the piston, a beveled seat in the 110 lower end of the cylinder, the bushing having its beveled lower end engaging the seat,

the upper end of the bushing having a reduced part forming a shoulder and the cylinder having an annular recess at its upper end, the bottom of which is flush with the shoulder and notches communicating with said recess, a ring fitting in the recess and engaging the shoulder, ears on the ring en-

gaging the notches, bolts passing through the ears into the cylinder, the upper end of the cylinder having a key slot therein and 10 a key on the bushing engaging said slot.

In testimony whereof I affix my signature.

MILLARD F. WOODWARD.
